UNITED STATES PATENT OFFICE.

JOHN E. GILL, OF FRANKLIN, PENNSYLVANIA.

CAR-AXLE LUBRICATOR.

SPECIFICATION forming part of Letters Patent No. 701,030, dated May 27, 1902.

Application filed August 3, 1901. Serial No. 70,760. (No model.)

To all whom it may concern:

Be it known that I, JOHN E. GILL, a citizen of the United States, residing at Franklin, in the county of Venango and State of Pennsylvania, have invented certain new and useful 5 Improvements in Car-Axle Lubricators, of which the following is a specification.

My invention relates to that class of devices especially intended for use in continuously and positively lubricating car-journals.

The object of my invention is to provide a device of this description of simple, durable, and inexpensive construction which may be readily inspected, removed, and replaced and 15 in which the parts may be quickly and inexpensively removed from time to time as may be desirable.

A further object of my invention is to dispense with the use of wicks or similar devices 20 for supplying oil by capillary action from an oil-reservoir to the lubricating-pad which is held in immediate contact with the car-journal.

These and such other objects as may hereinafter appear are attained by the devices 25 illustrated in the accompanying drawings, in which—

Figure 1 is a horizontal sectional view on the line 1 1 of Fig. 2 looking in the direction 30 indicated by the arrows. Fig. 2 is a cross-sectional view of an axle-box and journal fitted with the preferred form of my device on the line 2 2 of Fig. 1; and Fig. 3 is an enlarged detail of my device detached from the 35 journal-box.

Like letters of reference indicate the same parts in the several figures of the drawings.

Referring by letter to the accompanying drawings, A indicates a journal-box containing the car-journal B, upon which rests the bearing C. Arranged within the journal-box is an oil-receptacle and pad-support D, which 40 is provided with one or more supply-tubes E. These supply-tubes are arranged to project 45 through openings a in the side of the journal-box and preferably in such a manner as to also serve as a means for supporting the oil-receptacle D adjacent to the journal B.

Within the oil-receptacle D is fitted the lubricating-pad F, which rests upon a spring G, by means of which the pad is held constantly but yieldingly against the surface of

the car-journal. The oil-tubes E are provided at their outer ends with suitable caps e.

In assembling my device the spring G and 55 lubricating-pad F are placed within the oil-receptacle D, which is then inserted through the usual end opening in the journal-box and is held in position adjacent to the journal B while the oil-tubes E are inserted through the 60 openings a and attached to the oil-receptacle D. The oil-receptacle is then supplied with oil through the oil-tubes E, the caps e are attached, and the device is ready for use.

As the oilers inspect the car from time to 65 time, the oil-supply may be observed and renewed through the oil-tubes E. The lubricating device may be readily detached for inspection or renewal by merely detaching the tubes E from the receptacle D.

While I have shown and described my device in its preferred form comprising two supply-tubes which serve to support the device adjacent to the car-journal and with a continuous lubricating-pad supported within 75 the oil-reservoir by a single continuous spring, I do not wish to be understood as confining myself to these precise features of construction, as, obviously, the oil-supply tubes need not necessarily constitute the supporting 80 means, and so likewise the lubricating-pad and its supporting-spring may be varied, both as to form and number, without departing from the spirit of my invention.

Having thus described my invention, what 85 I claim, and desire to secure by Letters Patent, is—

1. The combination with a car-journal, of a journal-box, an oil-receptacle, means extending loosely through the side of the journal-box for supporting said oil-receptacle, and means for conveying oil from said receptacle to the car-journal, substantially as described.

2. The combination with a car-journal, of 95 a journal-box, an oil-receptacle, means extending loosely through the side of the journal-box for supporting said oil-receptacle adjacent to the car-journal, a lubricating-pad within said oil-receptacle, and means interposed between said pad and the bottom of 100 said oil-receptacle for holding said pad in yielding contact with the car-journal, substantially as described.

3. The combination with a car-journal, of a journal-box, an oil-receptacle, means for supporting said oil-receptacle within said journal-box, said means comprising a supply-pipe 5 extending from said oil-receptacle through the side of said journal-box, a lubricating-pad carried by said oil-receptacle, and means for holding said pad in contact with the car-journal, substantially as described.
- 10 4. The combination with a car-journal, of a journal-box, an oblong oil-receptacle, a plu-

rality of supply and supporting pipes extending from said oil-receptacle through one side of said journal-box, a lubricating-pad carried by said oil-receptacle, and means for holding 15 said pad in contact with the car-journal, substantially as described.

JOHN E. GILL.
